UNITED STATES PATENT OFFICE

167,907

VEHICLE TRIM LOUVER OR SIMILAR
ARTICLE

Charles H. Phaneuf, Royal Oak, Mich., assignor
to Packard Motor Car Company, Detroit, Mich.,
a corporation of Michigan

Application October 10, 1951, Serial No. 16,889

Term of patent 14 years

(CL. D14—6)

To all whom it may concern:

Be it known that I, Charles H. Phaneuf, a citizen of the United States, residing at Royal Oak, county of Oakland, State of Michigan, have invented a new, original, and ornamental Design for a Vehicle Trim Louver or Similar Article, of which the following is a specification, reference being had to the accompanying drawing, forming a part thereof.

Figure 1 is a side view of a vehicle trim louver showing my new design;

Figure 2 is an end elevation thereof;

Figure 3 is a bottom view of the louver shown in Figure 1; and

Figure 4 is a side perspective view thereof wherein the broken lines indicate the rear section of an automobile and are for the purposes of illustration only.

Those portions shown in the drawings by means of dotted lines are for illustrative purposes only.

I claim:

The ornamental design for a vehicle trim louver or similar article, substantially as shown and described.

CHARLES H. PHANEUF.
